MACHINE WITH ROTATING PLATFORM FOR
FILLING BAGS AND PILLOWS BY CENTRIF-
UGAL FORCE

Max Goldberg, New York, N. Y.

Application January 3, 1946, Serial No. 638,829

4 Claims. (Cl. 226—47)

1

This invention relates to a machine for filling casings of pillows and similar containers, with fibrous material such as kapok, etc.

An object of this invention is to provide a filling machine comprising a circular platform rotatably mounted on a shaft, the platform having a plurality of supports equally spaced around its circumference and providing vertical walls against which casings of pillows and the like may be suitably supported for rotation and to provide conduits or open top guide channels on the platform and leading directly into the casings to be filled.

Another object of this invention is to provide a distributor comprising a plurality of radially positioned blades and being mounted at the upper end of the platform shaft, the blades serving to distribute the filling material thrown thereon so that each of the conduits will receive a substantially equal amount of the filling material to be fed to the casings.

Another object of this invention is to provide a housing around the distributor and to provide a cone-shaped member at the central portion of the platform so that fibrous material thrown upon the cone will be distributed directly to the conduits and into the casings to be filled.

Another object of this invention is to provide a hopper centrally positioned in relation to the distributor whereby material fed into the hopper will be broken up by the distributor and confined by the housing around the distributor and made to follow downwardly into the conduits and into the casings to be filled.

Another object of this invention is to provide a power drive for the shaft whereby centrifugal force will be imparted to the fibrous material fed through the hopper and whereby the material will acquire sufficient force to enable it to forcibly enter into the casings and to forcibly eject the air therefrom and so that a densely packed product will result, it being immaterial whether the casings are porous or non-porous because the pressure imparted to the fibrous filling material due to the centrifugal force can be so controlled as to be more than sufficient to expel all the air from the casings and to densely pack the casings.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate cor-

2

responding parts throughout the several views, in which:

Figure 1 is a plan view of the filling machine, partly broken away.

5 Figure 2 is a central cross-sectional view, the section being taken as on line 2—2 in Figure 1.

Figure 3 is a front elevation of the filling machine, partly broken away to show an angular support for a fabric casing and a channel forming member, the fabric casing being removed.

10 Figure 4 is a fragmentary portion of the platform and showing a plan view of the support for the fabric casing and two of the channel forming members.

15 Figure 5 is a plan view of a distributor.

Figure 6 is a top plan view of a modified filling machine for filling individual containers such as a hassock mounted at the central portion of a revolving platform.

20 Figure 7 is a central cross-sectional view of the filling machine shown in Figure 6, the section being taken as on line 7—7 in Figure 6.

Figure 8 is a top plan view of a modified filling machine designed for filling two containers positioned at diametrically opposite points of a revolving platform, the machine being mounted below the floor level and a fragmentary portion of a grill being shown.

25 Figure 9 is a central cross-sectional view of the modified filling machine shown in Figure 8, the section being taken as on line 9—9 in Figure 8.

In the illustrated embodiment of the invention, the numeral 10 indicates a filling machine comprising a rotatable disk-shaped platform 11 having a plurality of angular supports 12 having converging vertical walls for supporting fabric casings. Each support is suitably fixed at its outer periphery. The platform 11 is fixed to a vertically mounted shaft 14 which is suitably supported by bearings 15 and rotated by a motor 16. A cone 17 is fixed to the upper face of the rotatable platform 11. At the upper end of the shaft 14 is a distributor 18 having radially positioned upright vanes 19 equally spaced around its circumference.

30 A stationary housing or casing 20 encloses the platform 11 and carries a plurality of arms 26 which support an inverted cup-shaped member 21. The member 21 encloses the distributor 18 and has a central opening 22 in its upper face. A hopper 23 is carried by a perforated support 27 secured to the member 21. The hopper extends into the member 21 through the opening 22 and provides means whereby fibrous filling material 35 may be dropped upon the distributor. Open top

guide channels 24 are formed by angles 28 suitably fixed to the platform 11 and extend from the cone 17 into fabric casings 25 lying in the angular supports 12. The lower face of the member 21 terminates adjacent the open top guide channels. The vertices of opposite angular supports are diametrically positioned. When the filling material is dropped into the hopper 23, the distributor vanes 19 feed the material radially and the member 21 directs the material downwardly to the rotatable platform 11.

Due to the centrifugal force developed by rotation of the platform 11, the fibrous material thrown into the hopper acquires centrifugal force tending to throw it outwardly from the rotatable platform and this force causes the material to be forcibly fed into the casings under great pressure. This pressure forces the entrained air out of the fabric casings 25 and permits dense packing of the fabric casings even though the fabric is made of non-porous material which does not permit air to escape outwardly therethrough.

The air is forcibly ejected from the fabric casings or containers by the filling material which enters the casings under great pressure caused by the centrifugal force. It is possible for the operator to increase or decrease the speed of rotation and the resulting centrifugal force, and to provide more or less pressure on the filling material so that the casings may be filled rapidly and densely.

Figures 6 and 7 show a modified filling machine 35 comprising a rotatable disk-shaped platform 36 carrying an upper casing section 37 and a lower casing section 38 which are held in unitary relation by wing nuts 39 threaded upon pivotally mounted bolts 40. The casing sections 37 and 38 are of the same circular cross-section. The interior of the lower casing 38 has a mold section 41. The interior of the upper casing section 37 has a complementary mold section 42. In the illustration shown the interiors of the mold sections are in the shape of a hexagon and are designed to receive fabric casing such as that used for a hexagon-shaped hassock 43 or the like. Mounted on pivot pins 44 on the upper mold casing section 37 are a plurality of gripping rods 45 having arcuate ends 46. The arcuate ends 46 serve to grip and support the neck portion of the hassock casing 43. Supported on the top of the upper mold section 37 by suitable angle members 48 is a hopper 49.

The platform 36 is mounted on a vertical shaft 50 which is suitably supported by bearings 51 and rotated by a belt 52 from a motor (not shown).

It is to be noted that slots 47 have been provided in the lower portion of the hopper 49, for the purpose of clearing the arcuate ends 46 of the rods 45 in their upward movement out of the hassock as is the case when a filled hassock is removed and replaced with an empty one.

The filling material is fed into the hopper 49 and enters the hassock casing 43, and, due to the centrifugal force developed by the rotation of the platform 36 the fibrous material fed through the hopper tends to move radially and acquires centrifugal force which throws the material radially outwardly and this force causes the material to be forcibly fed into the hassock casing under pressure. This pressure forces the entrained air out of the casing 43 and permits dense packing of the hassock casing.

Figures 8 and 9 show another modified filling machine 55 designed for filling two casings 56

suitably held by angular supports 57 on a rotatable platform 58. The casings are held at diametrically opposite points of the rotatable platform. The platform is supported on a frame 59 and rotated by a shaft 60.

A protective cover, preferably made of wire grill work 61 is positioned horizontally in line with the upper surface of the floor 62 of the operating room.

It is to be noted that the filling machine disclosed in Figures 8 and 9 is preferably sunk below the floor level. Supported by angle members 63 is a hopper 64 through which the material is fed downwardly.

Suitably fixed to the revolving platform 58 is a receptacle 65 having two radially extending ducts 66 leading into guide channels 67. The guide channels 67 are secured to the platform by angle irons 68. The neck portions 69 of the casings 56 to be filled are secured by cords 70 passing around the guide channels 67.

Due to the centrifugal force developed by the rotation of the platform 58 the fibrous material fed into the hopper 64 tends to move radially and acquires centrifugal force which throws the material radially outwardly into the guide channels and forcibly feeds the material into the casings 56 under pressure. This pressure forces the entrained air out of the fabric casings and permits dense packing of the fabric casings even though the fabric is made of non-porous material.

It is to be noted that due to the substantial quantity of material fed through the hopper, after the central portion of the hassock casing is covered the additional material fed into the casing is fed away from the center of the machine and this additional material is thrown radially outwardly by the centrifugal force and acquires a continually increasing force radially outwardly.

In accordance with the patent statutes I have described and illustrated the preferred embodiments of my invention, but it will be understood that various changes and modifications can be made therein without departing from the spirit of the invention as defined by the appended claims.

I claim:

1. In a machine for filling containers with fibrous material, a casing having a stationary hopper and means for rotatably supporting a shaft in upright position, a disk-shaped platform fixed to said shaft and rotatably mounted in said casing, said platform having a plurality of angular supports spaced around its circumference and providing converging vertical walls against which containers to be filled may be placed and held against movement during rotation, a cone-shaped member mounted axially on said shaft above said platform, and with the base of said cone in contact with said platform, open top guide channels fixed to said platform and leading from said cone directly into openings in said containers, a distributor having radially positioned blades and being fixedly mounted on said shaft above said cone and above said platform, said blades serving to feed said fibrous material radially outwardly, an inverted cup-shaped member enclosing said distributor for directing said material downwardly and means for rotating said shaft and causing centrifugal force to be imparted to said filling material whereby said material will forcibly enter and fill said containers and simultaneously eject the air therefrom through said openings.

2. In a machine for filling containers with fi-

brous material, a casing having a stationary hopper and means for rotatably supporting a shaft in upright position, a disk-shaped platform fixed to said shaft and rotatably mounted in said casing, said platform having a plurality of angular supports spaced around its circumference and providing converging vertical walls against which containers to be filled may be placed and held against movement during rotation, the vertices of opposite angular supports being diametrically positioned, a cone-shaped member mounted axially on said shaft above said platform, and with the base of said cone in contact with said platform, open top guide channels fixed to said platform and leading from said cone directly into openings in said containers, a distributor having radially positioned blades and being fixedly mounted on said shaft above said cone and above said platform, said blades serving to feed said fibrous material radially outwardly, an inverted cup-shaped member enclosing said distributor for directing said material downwardly, said cup-shaped member terminating at its lower face adjacent said open top guide channels, and means for rotating said shaft and causing centrifugal force to be imparted to said filling material whereby said material will forcibly enter and fill said containers and simultaneously eject the air therefrom through said openings.

3. In a machine for filling containers with fibrous material, a casing having a stationary hopper and means for rotatably supporting a shaft in upright position, a disk-shaped platform fixed to said shaft and rotatably mounted in said casing, said platform having a plurality of angular supports spaced around its circumference and providing converging vertical walls against which containers to be filled may be placed and held against movement during rotation, the vertices of opposite angular supports being diametrically positioned, open top guide channels fixed to said

platform, a distributor having radially positioned blades and being fixedly mounted on said shaft in spaced relation above said platform, said blades serving to feed said fibrous material radially outwardly, an inverted cup-shaped member enclosing said distributor for directing said material downwardly, said cup-shaped member terminating at its lower face adjacent said open top guide channels, and means for rotating said shaft and causing centrifugal force to be imparted to said filling material whereby said material will forcibly enter and fill said containers and simultaneously eject the air therefrom through said openings.

4. In a machine for filling containers with fibrous material, a casing having a stationary hopper and means for rotatably supporting a shaft in upright position, a disk-shaped platform fixed to said shaft and rotatably mounted in said casing, said platform having a plurality of angular supports spaced around its circumference and providing converging vertical walls against which containers to be filled may be placed and held against movement during rotation, the vertices of opposite angular supports being diametrically positioned, open top guide channels fixed to said platform, means circumscribing said hopper for directing material to said guide channels, and means for rotating said shaft and causing centrifugal force to be imparted to said filling material whereby said material will forcibly enter and fill said containers and simultaneously eject the air therefrom through said openings.

MAX GOLDBERG.
